UNITED STATES PATENT OFFICE.

EDWIN F. HARDEY, OF KANSAS CITY, MISSOURI.

RAZOR-BLADE HOLDER.

Application filed February 18, 1927. Serial No. 169,330.

My invention relates to a device for holding a safety razor blade so that the latter can be readily stropped, or utilized for various purposes such, for instance, as a paint 5 scraper, corn trimmer, seam ripper, eraser, and as a general utility knife.

One object of the invention is to provide a simple and inexpensive holder embodying two spring plates between which the razor 10 blade can be quickly and firmly clamped for use, or quickly released.

In order that the invention may be fully understood, reference will now be had to the accompanying drawing, in which:

Fig. 1 is a side elevation of the device holding a razor blade.

Fig. 2 is a longitudinal section on line 2—2 of Fig. 1.

Figs. 3 and 4 are detail side elevations of 20 the two spring plates embodying the invention.

Fig. 5 is a plan showing the manner in which the spring plates are bowed in opposite directions to each other.

Fig. 6 is a detail longitudinal sectional view of one of the spring plates.

In carrying out the invention I employ two complementary spring plates 2 and 4, which are slightly bowed longitudinally as 30 shown by Fig. 5. The spring plate 2 includes a handle member 6 and a blade clamping element 8, which latter is narrower than the former and tapers towards its outer end. The clamping element 8 is provided with a 35 hole 10 and a slot 12, and the handle member 6 is provided with an aperture 14 which is spaced a short distance from the slot 12. The hole 10, the slot 12 and the aperture 14 are preferably arranged along the longitudinal axis of the spring plate 2, as shown 40 more clearly by Fig. 3.

The spring plate 4 is similar in shape to the spring plate 2 and has a handle member 45 16 and a blade clamping element 18, which latter is narrower than the former and tapers towards its outer end. The blade clamping element 18 is provided with two lateral projections 20 and 22 which are spaced apart to enter the hole 10 and the 50 slot 12, respectively, of the clamping element 8. The handle member 16 is provided with a laterally projecting hook 24, which is spaced from the projection 22 and adapted to pass through the aperture 14 in the 55 handle member 6.

The projections 20 and 22 are preferably

pressed from the body of the clamping element 18, and the projection 20 has an abrupt shoulder 26 extending approximately at right angles to the clamping element 18 and 60 a sloping shoulder 28 which extends from the outer end of said shoulder 26 back to the body of the clamping element 18. The hook 24 has an end portion 30 approximately parallel to the handle member 16, for 65 a purpose which will hereinafter appear.

In the practical operation of the device the spring plate 4 is held with the projections 20 and 22 and the hook 24 uppermost. A safety razor blade A is then placed upon 70 the blade clamping element 18 in such position that the projections 20 and 22 will pass through the slots B and C near the opposite ends of said blade A. The plate 2 is then placed upon the plate 4 and the razor blade 75 A, with the aperture 14 disposed above the hook 24, after which the plates 2 and 4 are pressed toward each other and the plate 2 is then pushed backwardly, or to the right in drawing, to carry the edge 34 of the aperture 14 beneath the end portion 30 of the hook 24, which latter then holds the plates 80 2 and 4 together. When the plate 2 is pushed backwardly as stated, the hole 10 is carried into coincidence with the projection 85 20 over which it snaps so that the two clamping elements 8 and 18 may grip the opposite sides of the blade A and coact with the projections 20 and 22 in firmly holding said blade A in position. As the 90 clamping element 8 snaps into position as described, the edge 35 of the hole 10 is carried down into engagement with the abrupt shoulder 26, which latter coacts with the hook 24 in preventing accidental longitudinal 95 movement of the spring plate 2 in either direction upon the plate 4 and thus becoming disengaged from the latter.

As shown by Fig. 2, the rear end of the spring plate 2 slightly projects over the 100 corresponding end of the spring plate 4. Hence, when it is desired to remove the blade A it is only necessary to tap said projecting end against a table or other object 105 for the purpose of forcing the plate 2 longitudinally of the plate 4 until the edge 34 of the aperture 14 passes from beneath the overlapping portion 30 of the hook 24. The longitudinal movement of the spring plate 2 is facilitated by the sloping shoulder 28, 110 which enables the rear margin of the hole 10 to readily slip over the projection 20.

The slot 12 is of such length as to permit the plate 2 to move longitudinally of the plate 4 during the act of engaging or disengaging said plates. The foregoing operations may be quickly accomplished and without danger of cutting the fingers on the sharp edges of the blade A.

From the foregoing description it is apparent that I have provided a blade holding device embodying the advantages above pointed out, and while I have shown and described the preferred construction, combination and arrangement of parts I reserve the right to all such changes and modifications as properly fall within the spirit and scope of the invention as claimed.

Having thus described my invention, what I claim and desire to secure by Letters Patent, is:

- 20 1. A device of the character described consisting of two spring plates slightly bowed in opposite directions, lateral projections on one of said plates adapted to enter openings in the companion plate and project through openings in a blade placed between said plates, and a hook projecting laterally from one of said plates and adapted to pass through an aperture in the other plate, said hook having a sloping surface for drawing the plates together and against the opposite sides of the blade and a surface paralleling the associate plate for coacting with one of the lateral projections in holding the plates together.
- 25 2. A device of the character described consisting of two plates slightly bowed in opposite directions, lateral projections on one of said plates adapted to enter a hole and a slot in the companion plate and project through openings in a blade placed between said plates, and a hook projecting laterally from one of said plates and adapted to pass

through an aperture in the other plate, said hook having a sloping surface for drawing the plates together and against the opposite sides of the blade and a surface paralleling the associate plate for coacting with one of the lateral projections in holding the plates together, one of which latter is slightly longer than the other.

3. A device of the character described consisting of two plates, lateral projections on one of said plates adapted to enter a hole and a slot in the companion plate and project through openings in a blade placed between said plates, one of said projections having an abrupt shoulder for engaging the margin of the hole in the companion plate and a shoulder sloping backwardly to the plate from said abrupt shoulder, and a hook projecting laterally from one of the plates and adapted to pass through an aperture in the other plate, said hook having a sloping surface approximately like said sloping shoulder and a surface paralleling the associate plate for engagement therewith.

4. A device of the character described consisting of two spring plates slightly bowed in opposite directions and provided with coacting handle members and coacting blade clamping elements, which latter are narrower than the former, lateral projections on one of said plates adapted to enter openings in the companion plate and project through openings in a blade placed between said plates, and a hook projecting laterally from one of said plates and adapted to pass through an aperture in the other plate, said hook having a surface for engaging the apertured plate to hold the latter against the companion plate.

In testimony whereof I affix my signature.

EDWIN F. HARDEY.
